PAGE 2

Fig. 4

Fig. 3

FIG. 5

FIG. 6

FIG. 1 is a side elevational view of a poultry neck cutter showing my new design and taken from the left side of FIG. 3.

FIG. 2 is a side elevational view taken from the right side of FIG. 3.

FIG. 3 is a front elevational view of my design.

FIG. 4 is a rear elevational view of my design.

FIG. 5 is a top view of my design; and

FIG. 6 is a bottom view of my design.

I claim:

The ornamental design for a poultry neck cutter, as shown.
